UNITED STATES PATENT OFFICE.

HENRY A. NEUWILLER, OF NEW ORLEANS, LOUISIANA.

WIND-HORN.

1,264,841.

Specification of Letters Patent.

Patented Apr. 30, 1918.

Application filed September 30, 1916. Serial No. 123,128.

To all whom it may concern:

Be it known that I, HENRY A. NEUWILLER, a citizen of the United States, residing at New Orleans, in the county of 5 Orleans and State of Louisiana, have invented new and useful Improvements in Wind-Horns, of which the following is a specification.

This invention relates to improvements 10 in wind horns and has particular application to a horn wherein the air currents are generated by means of a motor driven fan.

In carrying out the present invention it 15 is my purpose to provide an air horn which will embrace the desired features of simplicity, efficiency and durability and which may be manufactured and marketed at a small cost.

It is also my purpose to provide a wind 20 horn which may be readily installed in a motor vehicle or the like so as to serve as a warning signal.

With the above recited objects in view 25 and others of a similar nature the invention consists in the construction, combination and arrangement of parts set forth in and falling within the scope of the appended claim.

In the accompanying drawing:—

30 The figure is a longitudinal sectional view through a wind horn constructed in accordance with the present invention.

Referring now to the drawing in detail 1 35 designates a funnel-shaped casing having the restricted end thereof formed with a tortuous neck 2 and the outer end of the neck 2 is connected with a bell 3 arranged opposite to the casing 1 and having the outer end covered by a screen 4 to prevent entrance of dirt and other foreign matter to

the horn. The larger end of the casing 1 is formed with an outwardly extending flange 5 and connected to the flange 5 is the periphery of a disk 15 having an upstruck or raised center 14, around which latter is 45 fitted a cylindrical drum 6 carrying an electric motor 7. Connected to the armature shaft of the motor 7 is a fan 8 arranged within the outer end of the casing 1, while formed in the disk around the drum are air 50 holes 9 covered by a screen 10. Arranged in the small end of the casing 1 at the junction of the latter with the neck 2 are reeds 11 differently toned.

In practice, when the motor 7 is energized 55 the fan 8 is revolved and draws air through the holes 9 and forces such air past the reeds 11 through the neck 2 and the bell 3 thereby vibrating the reeds 11 to sound the horn.

What is claimed is:—

The herein described wind horn comprising a funnel-shaped casing having an annular flange at its larger end, a neck connected with its smaller end and leading to a bell mouth, reeds located within said 65 smaller end, a disk closing the larger end of the casing and secured to its flange, the disk having air-inlet holes around its edge and an upstruck center, a drum whose inner end is fitted around said upstruck center, a 70 motor within the drum having its shaft carried through said disk at the center of the same, and a fan on the projecting end of said shaft and whose blades extend past said inlet holes whereby the rotation of the 75 fan draws air into said holes and forces it through the reeds, for the purpose set forth.

In testimony whereof I affix my signature.

HENRY A. NEUWILLER.
